THREAD ADVANCING REEL

Kenneth M. McLellan, Cleveland, Ohio, assignor
to Industrial Rayon Corporation, Cleveland,
Ohio, a corporation of Delaware

Application September 24, 1949, Serial No. 117,650

6 Claims. (Cl. 28—71.7)

1

This invention relates to thread advancing reels and more particularly, to reels having peripheries formed of a plurality of bar members used in the processing of the thread and the like.

In the spinning of filamentary material such as viscose rayon yarn, thread and the like, the filamentary material is withdrawn from a liquid bath by a take-up or withdrawing reel, and then it is led for further processing to subsequent reels or collecting or treating stations. Because of discontinuous peripheries of bar type reels the thread, during certain processing steps, is subject to barre affects which it is desirable to eliminate. There is a tendency toward barre in the initial withdrawing period for along with the thread there is also withdrawn amounts of liquid from the bath that is carried onto the reel to disturb normal contact of the still tender thread with the bar members because of an intervening layer of liquid between the reel bar surfaces and irregular thread and bar contact.

At a nominal spinning rate of about 80 meters per minute and using about five inch diameter bar-type reels of the type described in the Knebusch Patent 2,210,914, the volume of withdrawn bath liquids is not objectionable since not too great a quantity of bath liquids adheres to the thread; and the excess can be wiped off prior to the take-up reel substantially without injury or alteration of subsequent desirable thread characteristics. At increased speeds, however, the withdrawn thread tends to carry greater quantities of bath liquids so that a wiping device is not desirable since it introduces drag, and it becomes ineffective; also the yarn only intermittently contacts the wiping device because of the increased adhering liquid to affect the thread characteristics, for instance, dyeing. Further, should no wiping device be used at increased speeds the bath liquids nevertheless have been found to be objectionable on the reels since they tend to disturb the travel of the thread on the take-up reel because of intermittent contact with the supporting bars to affect dyeing characteristics.

Also in a further processing step, that of drying, barre effects tend to appear because of initial intermittent contact with the spaced hot bars of a drier reel. The thread in its initial travel over a heated reel, rests on heated spaced supports and the supported thread sections are first dried while the intervening unsupported lengths are dried later. This initial unequal drying tends, also, to affect thread dyeing characteristics.

Thread advancing devices having peripheries

2

of spaced interdigitating bars are advantageously utilized in the processing of thread since they comprise efficient and unitary structures that occupy a minimum of space, and also, they are adapted to advantageous arrangements facilitating the processing of thread. The spacing of thread contact areas of bar members, however, provides for a discontinuous circular support which is disadvantageous in the aforesaid processing steps. Excess liquid will adhere to the unsupported thread section while other quantities are forced outwardly in the supported sections. Eventually, of course, the entire length of the thread in its travel will be subjected to support by the bar members but the initial intermittent contact generally affects the thread in a manner so as to form barre.

This invention advantageously provides for a modified reel of the Knebusch type, although it is not limited thereto, that is adapted as a processing reel, a take-up or withdrawing reel, and as a drier reel. As a withdrawing reel it will substantially immediately throw off the spin bath liquids that are carried onto its periphery by the withdrawn thread and yet provide for sufficient thread travel control. The reel is used, generally, without a previous thread wiping guide. The periphery of the reel comprises a plurality of thread storing and advancing bar members having initial tapered portions at the thread take-up end, then normal thread contacting portions for the remainder of their lengths. The taper of the bars provides for a minimum thread contacting area thus, a minimum liquid adhering area while the subsequent full sized sections provide for a full support of the thread to give proper control of travel and, if desired, to enable a further liquid treatment of the yarn while it is still on the reel. By minimizing the initial thread contact area of the bar members and by their taper, the spin bath fluids are flung off substantially immediately. When such bars form the periphery of a drier reel of the type described in Patent 2,294,866 or one similar thereto wet thread is more slowly heated so that it is substantially entirely of the same temperature by the time it passes over the full heated bars. The gradual heating advantageously dries the thread more uniformly.

50 Either one or both sets of bars forming a reel can be tapered. The bar taper generally is desirable only for that portion of the reel that is sufficient to throw off the bath liquids or to precondition the thread by slowly heating it, and thereafter the bars can be of normal contacting

areas; the return to a normal contacting area permits a better control of the yarn on a reel, particularly, if a liquid treatment is to be applied.

The reel of this invention is described in further detail in the following specification in connection with the accompanying drawing, where:

Fig. 1 represents a schematic arrangement of a portion of a yarn, thread or the like spinning machine;

Figure 2 represents the withdrawing reel in front elevation;

Figure 3 is a side elevation of the withdrawing reel of Figure 2;

Figure 4 is a section in elevation of the reel of Figure 3; and

Figure 5 is a cross section of Figure 3 taken along lines 5—5.

Referring to the drawing there is shown positioned in a coagulating bath 10 a spinneret 11 at the end of a viscose rayon conducting mass tube 12. Viscose is extruded through the spinneret 11 into the bath 10 to form a thread or yarn. The thread 14 is withdrawn from the bath by a withdrawing or take-up reel 15 positioned above the coagulating bath 10. The thread 14 is led directly to the reel 15 over which it is advanced in a plurality of generally helical turns to a desirable take-off point on its periphery from whence it is led to a subsequent heated reel 16 whereon it may be dried. A liquid treatment, for instance a washing step, advantageously can be applied on the far end of the take-up reel 15 if desired. The thread can be led from a reel to a subsequent reel until a desirable number of processing steps are performed to provide a product having desirable characteristics.

As the thread is withdrawn from the coagulating bath 10, it carries with it quantities of the bath liquid 10. The quantities carried increase as the rate of withdrawal of the thread 14 increases and, depending upon the rate of carry over of the bath liquid, control of the thread on the reel may be disturbed which may result in poor yarn. The dyeing characteristics of the yarn are also affected due to intermittent initial contact of the still tender thread with the bars of the reel 15. It is desirable therefore to rid the reel of the excess bath liquid as quickly as possible and to minimize wet yarn contact with the bar members. Since guides before a take-up reel are not desirable or effective in adequately eliminating excess bath liquid the reel itself advantageously is adapted to rid the reel periphery of the bath fluid in a substantially quick and efficient manner.

The reel 15 is of the type disclosed in the Knebusch Patent 2,210,914 and the Jordan Patent 2,210,920 and it comprises two sets of bar members 19, 20 forming reel members 21, 21a that are positioned relative each other in an offset and askew manner so as to cause thread to travel in a general helix. The bar members form rigid reel members, one reel member 21 being concentric to the reel shaft 17 while the other is positioned about an eccentric whose axis is offset and askew to the reel shaft. The eccentrically mounted reel member 21a is adapted to rotate freely about its support while the concentric reel member 21 is firmly attached to the reel shaft 17 so that it is adapted to rotate therewith. Since the bar members interdigitate the concentric reel member 21 is adapted to drive the eccentric reel member 21a either through bar to bar contact or through a suitable gear arrangement.

The reel of Figures 3 and 4 generally comprises such an aforesaid arrangement. The bars 19 of the reel member 21 are concentric to the reel shaft 17. Bars 20 form the eccentrically positioned reel member 21a that is attached by means of a ring 24 into which the bars merge, and which ring 24 is secured to a flange 25 by means of bolts 27. Flange 25, in turn, forms a part of sleeve 30. The sleeve 30 is adapted to rotate about an eccentric (not shown) that is positioned about the reel shaft 17. Since the eccentric is held stationary it generally forms part of a reel supporting structure such as the flange 31 about the reel shaft 17. The reel is then advantageously supported by the flange 31 in the face of a spinning machine. The reel 15 is driven by means of the gear 33 mounted at substantially the shaft end to which it is secured in a suitable and desirable manner for instance by a set screw 34.

The bar members 19, 20 of the reel 15 at the take-up end and for a desired distance thereafter advantageously are tapered to a practical minimum which may be as narrow as one-sixteenth inch at the periphery from a normal width of about one-fourth to one-half inches. The tapered sections 22, 23 of the bar members 19, 20 are narrowed toward the yarn bearing surfaces to areas adapted to provide sufficient thread support while still permitting a substantial control of the thread. Because of the taper the bar members 19, 20 tend to minimize the liquid adhering area with the result that they more readily fling off the bath liquids since a substantial portion of liquid supporting and adhering surface has been eliminated. The direction of the taper also tends to more readily throw off liquids. Such a reel periphery thus provides a substantially fluid-free thread for the remainder of the reel and for a subsequent processing treatment. Further thread and bar contacts are minimized by such a bar construction substantially eliminating undesirable effects on the thread.

As shown in Figures 3 and 5, both sets of bars 19, 20 are tapered in the direction of the reel periphery. At increased speeds where centrifugal action is, to an extent, depended upon to throw off the liquids on a reel the tapered bar members facilitate such a removal yet their speed of rotation need not be such so as to depend on centrifugal forces entirely. Where reel speeds are not of such a rate so as to carry over unusual amounts of bath fluid then a reel having a single set of tapered bar members will generally eliminate the interfering quantities of bath fluids. Where spinning speeds are increased, however, to rates that tend to carry substantial quantities of a bath liquid on to the reel, then it is advantageous to have all bars tapered since liquids will be then more readily discarded from the reels.

The taper of bars 19 and 20 may extend substantially throughout length or only for a portion. The length of the taper is, of course, dependent on the amount of fluid carried over from the bath, and on the speed of the reel.

In instances where a washing treatment, or a further light acid application is desirable on the take-up reel 15 the bar members 19, 20 are advantageously brought to a normal peripheral width to provide sufficient thread bearing areas for holding the treatment liquids. As shown in Figure 1 a preliminary yarn treatment is applied to the reel 15 at substantially the opposite end of the reel from the take-up end. The thread 14 is made substantially free of the bath liquids 75 by the time the treatment is applied. Since

speeds that tend to throw off treating liquids may be used a liquid treatment distributing and maintaining blanket 36 advantageously may be utilized while the distributing tube 35 applies the treatment liquid. A treatment thus may be applied, maintained, and spread over a predetermined yarn area.

The reel 16 is of generally the same construction except that it is heated by circulating a heating fluid such as steam, hot water, etc. through its interior in the manner disclosed in the Bergmann Patent 2,294,866. The bar members are advantageously tapered as those of reel 15. Wet thread is supported on bar members having a minimum thread supporting area for a desired interval of time until the thread is pre-dried and then progressively raised to the full bar temperature. Whatever markings are made on the thread on the reduced area bar members they are minimized in length or size and spaced so that the dyeing qualities of the thread are hardly affected. Generally processing reels for steps other than drying are reduced from a width of one-fourth inch to a sixteenth, and dryer reels from a half-inch to a sixteenth.

I claim:

1. A thread storing, thread advancing reel comprising two sets of interdigitating bar members cooperating in a manner so as to advance thread and the like in the form of a general helix, and both of said sets of bar members having reduced thread contacting areas for a portion of their lengths, and said reduced areas being at the initial thread take-up end of the reel.

2. A thread storing, thread advancing reel comprising, two sets of interdigitating bar members, one of said sets being positioned offset and askew to the other, said sets upon rotation cooperating in a manner so as to advance thread and the like in the form of a general helix, and both of said sets of bar members having reduced thread contacting areas for a portion of their lengths, and said reduced areas being at the initial thread take-up end of the reel.

3. A thread storing, thread advancing reel comprising two sets of interdigitating bar members, one of said bar members being offset and askew to the other, said sets of bar members when rotated cooperating in a manner so as to advance thread and the like in the form of a general helix, both of said sets of bar members having reduced thread contacting areas for a

portion of their lengths, the reduced areas being at the initial reduced take-up end of the reel, and said reduced thread contacting areas being arcuate in shape.

5 4. A thread storing, thread advancing reel comprising, two sets of interdigitating bar members, one of said sets being offset and askew to the other, said sets cooperating in a manner so as to advance thread and the like in the form of a general helix, both of said sets of bar members having reduced thread contacting areas for a portion of their lengths, said reduced areas being at the initial thread take-up end of the reel, and said reduced bar members being tapered in the direction of the reel periphery.

10 5. A thread storing, thread advancing reel comprising, two sets of interdigitating bar members, one of said sets being offset and askew to the other, said sets cooperating in a manner so as to advance thread and the like in the form of a general helix, both of said sets of bar members having reduced thread contacting areas for a portion of their lengths, said bar members being reduced from about one-half inch in width

15 to about one-sixteenth inch for a portion of their lengths at the initial thread take-up end of the reel.

20 6. A thread storing, thread advancing reel comprising, two sets of interdigitating bar members, one of said sets being offset and askew to the other, said sets cooperating in a manner so as to advance thread and the like in the form of a general helix, both of said sets of bar members having reduced thread contacting areas for a portion of their lengths, said bar members having a reduced width of about one-sixteenth inch for a portion of their lengths at the initial thread take-up end then a normal width of about between a quarter to one-half inch.

25 40 KENNETH M. McLELLAN.
